UNITED STATES PATENT OFFICE.

JAMES C. FRENCH, OF CHICAGO, ILLINOIS, ASSIGNOR TO FREDERICK C. AUSTIN, OF CHICAGO, ILLINOIS.

MIXING-MACHINE-CHARGING HOPPER.

1,278,131.

Specification of Letters Patent. Patented Sept. 10, 1918.

Application filed October 18, 1917. Serial No. 197,213.

To all whom it may concern:

Be it known that I, JAMES C. FRENCH, a citizen of the United States of America, and resident of Chicago, county of Cook, 5 and State of Illinois, have invented a certain new and useful Improvement in Mixing-Machine-Charging Hoppers, of which the following is a specification.

This invention relates to charging hoppers for mixing machines, or for other machines, of that kind in which the hopper is mounted to swing up and down, being arranged to rest upon or close to the ground when in position to receive the materials, 15 and being raised into an inclined position when it is desired to discharge the materials into the machine.

Generally stated, the object of the invention is to provide an improved tilting or 20 swinging hopper of the foregoing general character.

A special object is to provide an improved construction and arrangement tending to facilitate the operation of the hopper, 25 and tending to render it more durable and less liable to get out of order, as well as better calculated to discharge the materials promptly and quickly into the machine, in the desired or necessary manner, as will 30 hereinafter more fully appear.

It is also an object to provide certain details of construction tending to increase the general efficiency and serviceability of a charging hopper of this particular character.

To the foregoing and other useful ends, the invention consists in matters herein-after set forth and claimed.

In the accompanying drawings:

40 Figure 1 is a side elevation of a mixing machine provided with a charging hopper embodying the principles of said invention. Fig. 2 is a plan of said machine.

As thus illustrated, this invention comprises a vehicle or portable body A upon which is mounted the rotary mixing receptacle B, the latter being of any suitable or well-known type or form. As shown, the mixing receptacle has an inlet opening 45 at its front side 1 and an outlet opening at its rear side 2, so that the mixture is discharged by the usual spout 3 in the well-known manner. A frame C is also mounted on the vehicle body. The mixing machine 50 is operated by an engine D, of any suitable

character, connected in any desired manner with the mixing receptacle B, so that the latter is rotated to mix the materials. Also, the rear wheels 4 of the vehicle body are driven by said engine through the medium 60 of suitable connections. In this way, the mixer may travel along the street and is adapted for use for various purposes, such as the mixing of concrete for paving or sidewalks, or for building purposes.

The hopper E has the general form of a pan, and is pivoted at e upon the arms F, there being two of these arms, one at each side of the machine, and said arms being pivoted at f upon a transverse shaft supported in brackets 5 mounted on the body of the vehicle. The pivot e has opposite end portions 6 which are adapted to engage the bumpers 7 on the frame of the machine, when the hopper is raised (see dotted lines 75 in Figure 1), and whereby the upward movement of the arms F is limited. The outer and lower ends of these arms are provided with a transverse element 8 which engages the bottom of the hopper, thereby 80 to limit the relative movement between the hopper and the arms about the pivot e, and whereby the hopper is supported on the arms when raised. The cable G engages the sheave 9 on the hopper and also the 85 sheave 10 on the top of the frame C, and has one end thereof secured at 11 to said frame adjacent said last mentioned sheave. The other end portion of said cable is wound upon the drum g, which is suitably mounted 90 on the vehicle body, and which is operated in any suitable manner by power communicated thereto from said engine. Therefore, when the cable G is operated, the hopper E is raised, but the weight thereof keeps 95 the bottom of the hopper against the transverse member 8 of the tilting support formed by the arms F, in a manner that will be readily understood. In this way, the hopper E and the arms F swing upward about 100 the transverse axis provided by the pivot shaft f, and this condition is maintained until the hub portions 6 strike the bumpers 7, which latter are near the intake opening 1 of the mixing receptacle. As soon as this 105 occurs, the upward movement of the arms F ceases, but the continued operation of the cable G serves to pull the hopper E upward a little farther, as it is free to tilt about the pivot e until the materials are dis- 110

charged into the mixing receptacle. In this way, a bumping action is obtained, and a final tilting of the hopper is insured, sufficient to insure a quick discharge of the materials into the receptacle, as soon as the hopper reaches its discharge position. This is advantageous, it will be seen, as otherwise the materials might stick in the hopper and refuse to slide downward therein, and in such a case some of the materials would travel back to the ground with the hopper. Also, with the hopper pivoted at *e*, the lower end of the support formed by the arms *F*, and which lower end is formed in part by the transverse member *8*, may rest upon the top of the body *A*, at the end of the latter, but the hopper can assume a position in accordance with the surface of the ground below it—that is to say, it can rest on an elevation which will tilt it upward a little from the position shown in the drawings. In such case, the support formed by the two arms *F* remains in its tilted position, with its lower end resting on the body *A*, but the hopper is adapted to rest on the cross-member *8*, if there is nothing below the hopper, or may rest directly on the ground if such is desirable. It will also be seen that the pivot *e* is maintained above the horizontal plane of the stationary axis *f*, as the arms *F* rest upon the body of the machine when the hopper *E* is in loading position. In this way, the horizontal and transverse axis provided by the pivot *e* can remain stationary while the hopper *E* is tilted upward by hand, or by resting on an elevation on the ground; but the pivots and various axes are so relatively arranged, it will be seen, that a pull on the cable swings both the hopper and its support upward in unison without any relative motion between them until the bumper is reached, and the support remains stationary while the hopper tilts a little farther. Materials are shoveled or wheeled into the hopper and as soon as a load is accumulated the hopper is raised into the discharge position thereof.

The flat top or rear surface of the support formed by the arms *F* forms a stop to limit the relative movement between the hopper *E* and said support in one direction. When the hopper is on the ground, or in its lowered position, the transverse axis provided by the pivot *e* is considerably above the line drawn horizontally from the axis *f* to the axis *12* to which the sheave *9* is secured, so that in rising the weight of the hopper tends to keep its flat bottom surface against the said flat top of the support formed by the arms *F*, and there is no relative movement between said hopper and support until the pivotal joint *e* engages the stationary bumper, which latter is composed of three elements or portions *7* which are spaced apart a suitable distance and ar-

ranged practically directly above the axis *f*, whereby the axis or pivot *e* is sufficiently over or past the center, so to speak, when the arms *F* are raised against the bumper, to hold the hopper in discharging position. In other words, the axis *e* moves upward to a point where it is directly over the axis *f* and then moves a distance beyond and out of line vertically with said axis *f* before the bumper is reached. In this way, the hopper steadies itself in discharging position, and the arms *F* do not tend to fall backward while the discharge is taking place. When the hopper is lowered it moves downward until it rests against the flat top or surface of the support formed by the arms *F* and then the hopper and support swing down together about the axis *f*. In this way, the hopper has two axes of movement, one (the axis *f*) being stationary, and the other (the axis *e*) being movable.

What I claim as my invention is:

1. The combination of a body, means to provide a horizontal axis on said body, a tilting support on said axis, a hopper pivoted on said tilting support, whereby said hopper has both a stationary axis and a movable axis about which to swing up and down, said tilting support having a rigid portion serving as a stop to limit relative movement between said hopper and said support in one direction, each axis being disposed in fixed relation to said stop, whereby the movable axis is maintained a fixed distance from the stationary axis, a lifting connection applied to the hopper to raise the hopper and the tilting support in unison by movement thereof about said stationary axis, means to sustain the weight of said support in lowered position, and a bumper to engage said tilting support to limit the upward swinging motion thereof, so that said support will stand upright above its stationary axis, said hopper being movable a distance into discharge position while said tilting support is held stationary by said bumper.

2. A structure as specified in claim 1, in which said connection is provided with a transverse axis on the hopper, and the pivot between the hopper and said tilting support being above a line drawn from said stationary axis to said axis for the lifting connection when the hopper is being raised, said means serving to keep said pivot above the horizontal plane of said stationary axis.

3. A structure as specified in claim 1, said bumper comprising two portions spaced apart in position above said stationary axis, and the pivot between the hopper and said tilting support being provided with opposite end portions for engaging said bumper.

4. The combination of a body, means to provide a horizontal axis on said body, a tilting support on said axis, a hopper pivoted on said tilting support, whereby said hopper

per has both a stationary axis and a movable axis about which to swing up and down, said tilting support having a portion serving as a stop to limit relative movement between said hopper and said support in one direction, each axis being disposed in fixed relation to said stop, a lifting connection applied to the hopper to raise the hopper and the tilting support by movement thereof about said stationary axis, a bumper to engage said tilting support to limit the upward swinging motion thereof, said hop-

per being movable a distance into discharge position while said tilting support is held stationary by said bumper, and a stop to engage and thereby limit the downward movement of said tilting support, so that said hopper can be tilted upward while said tilting support remains stationary in lowered position.

Signed by me at Chicago, Cook county, Illinois, this 3rd day of October, 1917.

20

JAMES C. FRENCH.
